CLAIM

I claim the ornamental design for a pallet, as shown and described.

DESCRIPTION

FIG. 1 is a top plan view of the pallet;

FIG. 2 is a side elevational view of the pallet, the opposite side being a mirror image thereof;

FIG. 3 is an end elevational view of the pallet, the opposite end being a mirror image thereof;

FIG. 4 is a bottom plan view thereof;

FIG. 5 is a top perspective view thereof; and,

FIG. 6 is a bottom perspective view thereof.
